UNITED STATES PATENT OFFICE.

SAMUEL W. DECKER, OF JERSEY CITY, NEW JERSEY.

COMBINED WINDOW SCREEN AND VENTILATOR.

1,116,248.

Specification of Letters Patent.

Patented Nov. 3, 1914.

Application filed February 18, 1913. Serial No. 749,250.

To all whom it may concern:

Be it known that I, SAMUEL W. DECKER, citizen of the United States, residing at Jersey City, in the county of Hudson and State of New Jersey, have invented certain new and useful Improvements in Combined Window Screens and Ventilators, of which the following is a specification.

My invention relates to new and useful improvements in ventilating devices for windows and the object of my invention is to provide a device which may be detachably engaged in the window casing of an ordinary window and which will permit the opening of the window to as great an extent as desired and which will at the same time prevent a direct draft through the window upon any one in the room.

A further object of my invention is to so construct the device that even though the window be open to its widest extent no rain or snow can enter the room. And a still further object of my invention is to provide means by which the entrance of all insects through the open window will be prevented when the ventilator is in place.

With these and other objects in view, my invention will be more fully described, illustrated in the accompanying drawing and then specifically pointed out in the claims which are attached to and form a part of this application.

In the drawing, Figure 1 is a front elevation of a conventional form of window construction showing my ventilator in use. Fig. 2 is a vertical sectional view on the line 2—2 of Fig. 1; Fig. 3 is a transverse sectional view on the line 3—3 of Fig. 1, looking downwardly; Fig. 4 is a fragmentary sectional view taken on the line 4—4 of Fig. 3, showing the detachable mounting of the screen which forms a closure for the ventilator.

Corresponding and like parts are referred to in the following description and indicated in all the views of the drawing by the same reference characters.

The construction and operation of the preferred embodiment of my invention can best be illustrated in connection with a window of the usual construction, such as shown in Fig. 1, including a window casing 10 having a window sill 11, yoke 12 and pulley stiles 13 each provided with the usual inner parting beads 14, outer parting beads 15 and intermediate parting beads 16, between which

the upper and lower window sashes 17 and 18 slide.

All of the above described parts may be of the usual or any preferred construction with the exception that the inner parting beads 14 are provided throughout a portion of their length, at their lower ends, with inwardly extending vertical ribs or shoulders 19 which lie in spaced relation to the inner face of the side rails of the lower window sash and which terminate at their upper ends slightly below the central portion of the window casing for a reason which will be hereinafter apparent. These ribs or shoulders are preferably formed integrally with the parting beads but in case the ventilator is to be applied to windows already built and having the usual type of parting bead, the ribs or shoulders may be formed from separate strips of wood or metal secured to the parting bead. Furthermore, in connection with the ventilator the sill of the window casing is preferably provided with a strip of wood or metal 20 having an upwardly directed shoulder 21, this strip and shoulder forming in fact a horizontal continuation of the inner parting beads and their shoulders. This strip is not wholly essential but its employment is advantageous for reasons which will be explained.

The ventilator proper includes a substantially wedged shaped structure closed at its inner side, base and ends and open at its upper side and top. More particularly it includes an inner side member 22, substantially triangular shaped side members or wings 23 and a horizontal base 24, these parts being so constructed that the wings converge slightly toward each other at their free edges as clearly shown in Fig. 3 of the drawing, while the inner side member 22 is inclined inwardly away from the window from its lower to its upper end when the ventilator structure is in place. The free edges of the wings 23 are provided with laterally directed shoulders or ribs 25 which engage between the shoulders of the parting beads 14 and the lower window sash. The base 24 is also provided at its free edge with a downwardly depending rib or shoulder 26 which engages between the shoulder 21 and the window sash.

As will be readily apparent from the foregoing description the interengagement of the shoulders of the ventilator structure and the shoulders of the parting beads serves

2

to firmly lock the ventilating device in place. At the same time the ventilator may be readily removed from the window casing by raising the same to bring it above the upper ends of the shoulders 19 and so free it from the casing. This ventilator structure preferably terminates at its upper end on a level with the mid portion of the window and it will therefore be apparent that the lower window sash may be raised to any desired extent and that all air entering through the window will be deflected into the upper portion of the room by the inclined inner side member or wall 22 of the ventilator. Because of this any air in the room will be thoroughly protected from direct drafts through the window. It will also be noted that any rain or snow driven through the window, which would ordinarily enter the room, will also strike against the member 22 and wings and be turned back out of the window. In this connection, the strip 20 and strip engaging shoulder 26 of the ventilator play an important part in that they prevent the passage of any air or moisture into the room beneath the ventilator. Furthermore, they serve to space the base of the ventilator slightly above the window sill in such a manner that the hand 30 may be readily passed under the base when the ventilator is to be removed from the window. That portion of the ventilator structure above described may be formed of any suitable material such as wood or metal and if desired, the inner side of said structure may be formed of glass in order to avoid shutting light out of the room. For this reason I have illustrated the front member 22 in Fig. 1 as formed of wood or metal, while in Fig. 2 I have shown the use of a frame 27 carrying a pane of glass 28 as the inner member of the ventilator.

In order to prevent all entrance of insects into the room through the ventilator, when the window is open, I provide the upper end or top of the ventilator structure with a removable closure, indicated as a whole by the numeral 29. This closure includes a frame 30 covered with a screen of foraminous material, preferably wire screening, 31. The ends of this frame converge slightly toward each other as shown in Fig. 3 of the drawing, for close engagement between the wings 23 of the ventilator, the wings being extended at their upper ends slightly above the top of the inner side member 22 for this purpose. These extended portions of the wings are grooved horizontally as shown at 32 to receive tongues 33 formed along the end members of the frame 30 and it will therefore be apparent that the frame may be readily slipped into or out of place in the ventilator. The inner frame member is extended 65 somewhat at its ends as shown at 34 to

engage against the inner edges of the extended portions of the wings 23 and so stop the inward movement of the closure 29 and thus avoid all danger of breaking the glass of the window.

The outer member of the closure frame 30 is provided along its outer edge with a packing strip 35 of felt or rubber which, when the closure is in place, engages against the glass of the lower window sash to absolutely prevent the entrance of insects to the room. If the window sashes are of that type in which two or more panes of glass are mounted in each sash and separated by one or more vertically extending sash rails, such as are shown at 36 in Fig. 3 of the drawing, the outer member of the frame 30 will be notched as at 37 to seat about the sash rail to permit the closure to bear snugly against the window.

From the foregoing description, taken in connection with the drawing, the operation of my improved ventilator will be readily understood and any detailed description of the same is therefore unnecessary. It will be noted however, that when removing the ventilator from the window casing, the closure 29 should either be completely withdrawn from the ventilator previous to raising the latter, or should at least be drawn out to such a distance that it will not strike against the upper transverse sash bar of the lower window sash upon raising of the ventilator to free it from its guides.

By forming the body of the ventilator 100 with its inner side wider than its outer side, in the manner described, the air is more thoroughly distributed through the room and furthermore the positioning of the closure 29 is more readily accomplished as it 105 will not bind between the wings. Also no particular care is required in applying the closure to the ventilator as its narrow edge need only be rested upon the upper edge of the ventilator wall 22, the closure held in 110 horizontal position and moved inwardly, when its tongues will automatically seat in the grooves 22 to lock the closure in place. If deemed advisable, angular brackets or braces 38 may be employed to brace the 115 wings to the inner wall member of the ventilator as shown in Figs. 2 and 3 of the drawing.

Having thus described the invention, what is claimed as new is:

1. A ventilator including an inner side member, wings secured to the inner side member and converging toward each other at their free edges, a base, and a removable foraminous closure adapted for detachable engagement between the converging wings.

2. A ventilator structure including an inner side member, base and wings, and a removable closure for the top of said ventilator, said closure consisting of a screen of

foraminous material adapted for sliding engagement between the wings and provided with a packing strip for engagement against the glass of the window.

- o 3. A ventilator including an inclined inner side member, wings carried by the side member and having their inner faces provided with horizontal channels, and a top member having its edges slidably disposed in the channels, the wings at their free ends

converging toward each other and the top member being tapered from its front to its rear edge to correspond to the convergence of the wings.

In testimony whereof I affix my signature 15
in presence of two witnesses.

SAMUEL W. DECKER. [L.s.]
